(57) **CLAIM**

The ornamental design for food plate with beverage container receiving portion, as shown and described.

DESCRIPTION

FIG. 1 is a top left-hand isometric view of the food plate with beverage container receiving portion showing my new design;

FIG. 2 is a bottom right-hand isometric view thereof;
FIG. 3 is an end view thereof as seen by looking downward from the top portion of FIG. 4;

FIG. 4 is a top view thereof;
FIG. 5 is a bottom view thereof;
FIG. 6 is an end view thereof looking upward from the lower end of FIG. 5;
FIG. 7 is a left side view thereof; and,
FIG. 8 is a right side view thereof.
